No. 37,454.

Patented June 6, 1905.

UNITED STATES PATENT OFFICE.

GIBBS MASON, OF NEW YORK, N. Y., ASSIGNOR TO WIGHTMAN & HOUGH COMPANY, A CORPORATION OF RHODE ISLAND.

DESIGN FOR A LOCKET OR SIMILAR ARTICLE OF JEWELRY.

SPECIFICATION forming part of Design No. 37,454, dated June 6, 1905.

Application filed April 21, 1905. Serial No. 256,821. Term of patent 3½ years.

To all whom it may concern:

Be it known that I, GIBBS MASON, a citizen of the United States, residing at New York, in the county of New York and State of New York, have invented a new, original, and ornamental Design for Lockets or Similar Articles of Jewelry, of which the following is a specification, reference being had therein to the accompanying drawing.

The figure is a face view of a locket, showing my new design.

I claim—

The ornamental design for lockets and similar articles of jewelry as shown.

GIBBS MASON.
